CLAIM

The ornamental design for a knee therapy ice pack, as shown and described.

DESCRIPTION

FIG. 1 is a first perspective view of a knee therapy ice pack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The short-dash long-dash broken lines shown in FIGS. 2 and 9 depict boundaries of the enlarged view indicators and form no part of the claimed design.
